REMOTE CONTROL SYSTEM

George W. Baughman, Swissvale, Pa., assignor
to The Union Switch & Signal Company, Swiss-
vale, Pa., a corporation of Pennsylvania

Application September 9, 1944, Serial No. 553,395

7 Claims. (Cl. 177—353)

My invention relates to remote control systems, and more particularly to the line or communication circuits for such systems.

My invention is an improvement upon that disclosed in Letters Patent of the United States No. 2,350,668, issued June 6, 1944, to George W. Baughman and Norman F. Agnew, for Remote control systems, and upon that disclosed in an application for Letters Patent of the United States, Serial No. 552,504, filed September 2, 1944, by Lloyd V. Lewis.

One object of my invention is the provision of means for interposing a carrier current or radio channel in the line connecting the office and stations in a remote control system, using only one frequency channel for the transmission of codes in two directions.

Another object of my invention is the provision of means for transmitting carrier current codes in either direction between two stations, in which a sensitive receiver at each station, responsive to highly attenuated signals received from the other station, is arranged so that it does not respond to signals transmitted from the same station regardless of their strength or frequency, together with means for establishing one way transmission in the event codes are initiated at both stations at the same time.

I shall describe two forms of apparatus embodying my invention and shall then point out the novel features thereof in claims.

Referring to the accompanying drawings, Figs. 1A and 1B, taken together, show one form of remote control system embodying my invention in which code signals are transmitted by radio in two directions between the control office, shown in Fig. 1A, and a repeater station, shown in Fig. 1B, and connected to line wires Y1—Z1 over which the codes are transmitted between the repeater stations and a plurality of field stations, of which one is shown.

Fig. 2A shows a modification of Fig. 1A in which the apparatus for repeating the codes which originate at the office to the stations as radio signals and for repeating codes received as radio signals to the office is contained in a "first repeater station" located at a distance from the office and connected thereto by the line wires Y—Z.

Fig. 2B shows a modification of Fig. 1B in which a repeater similar to that of Fig. 1A is arranged to repeat the codes received from the office as radio signals into a second line Y2—Z2 as well as into line Y1—Z1, and is also adapted to repeat indication codes received from field stations on

either line to the office over the same radio channel.

Similar reference characters refer to similar parts in each of the views.

It is to be understood that the remote control system employed herein is of the "time code" type, employing coding units CU at the office and at each field station for transmitting and receiving the codes, such as is shown in Letters Patent of the United States No. 2,229,249, issued January 21, 1941 to Lloyd V. Lewis, for Remote control systems, but with the line circuits arranged as shown in Patent No. 2,350,668, hereinbefore referred to. As shown in Fig. 1B the line relay R at each station is of the biased polar type and is normally energized over the line wires Y1—Z1 by current from a line battery B1. The control codes originating at the office are transmitted over this line by periodically interrupting the battery current in the same manner as in Patent No. 2,229,249, but the indication codes originating at the stations are transmitted in a different manner, namely, by periodically connecting the line wires together through a low impedance comprising the filter coils LP at the transmitting station, so as to vary the current delivered by battery B1 in accordance with the code. These codes of current variations are received at the repeater station by a polar line relay IR connected to the line through a transformer 40 and thereby rendered responsive to the line current variations. Relay IR is of the magnetic stick type arranged to be held in its last operated position when deenergized and normally occupies the position in which its left-hand contacts are closed, as shown.

The repeater station apparatus as shown in Fig. 1B includes a pole changer relay IPC by which the polarity of the current supplied to the line is reversed during the transmission of an indication code, together with a group of slow release relays LA, LB and LC, a stick relay Z, and carrier current transmitting and receiving relays ITC and ICR. In addition, an electronic oscillator OSC is provided for generating alternating current of a suitable carrier frequency which is passed through an amplifier AMP and delivered over the front contacts of relay ITC to a radio antenna A1. Relay ITC repeats the code operation of relay IR and delivers the indication codes to antenna A1 for retransmission as radio signals. Relay ITC normally occupies a released position, as shown, in which antenna A1 is connected over its back contact b through an amplifier to relay ICR, which relay is responsive to codes of radio signals received from the office, and by the opera-

tion of its contact *a* retransmits them over line Y_1-Z_1 to the field stations.

The coding apparatus at each field station comprises a master relay *M*, which when energized places the station apparatus in the transmitting condition, a transmitter relay *T* which is operated periodically when relay *M* is energized, to deliver the indication code to the line, a line relay *R* of the biased polar type responsive to the codes delivered to the line relay *ICR* and also to those delivered by the associated relay *T*, and a coding unit *CU* comprising selecting apparatus for decoding the received codes and which also governs the operation of the associated relay *T*. Controlled by the coding unit, but shown separately, is a selecting relay *E* which responds selectively to the first step of a control code transmitted from the office to condition the unit to receive the code and to prevent further operation of the transmitter relay *T* in the event the office and station initiate codes at the same time, and a line bridging relay *LBP* which is energized for the duration of each code and controls various local circuits.

The apparatus at the control office, Fig. 1A, is generally similar to that at the stations, comprising a master relay *OM*, a transmitter relay *OT*, and a receiving relay *OR* governing a coding unit *CU*. Certain of the coding unit relays are shown separately in Fig. 1A, comprising the relays *OL1*, *OL2*, *OLB*, *OLBP*, *O18*, *PC* and *PCP*, all of which function like the similarly designated relays of Patent No. 2,350,668. In addition, an electronic oscillator *OSC* and an amplifier *AMP* are provided for delivering carrier current coded by the operation of the contact *b* of a relay *TC*, to a radio antenna *A*, relay *TC* repeating the code operation of the office transmitter relay *OT*. Relay *TC* normally stands released, and then antenna *A* is connected over its back contact *b* through an amplifier to the receiving relay *OR*, which relay is thus rendered responsive to the indication codes originating at the stations. An auxiliary relay *TS* is also provided, by which relay *OR* is controlled on the first step of an indication code as hereinafter explained.

As pointed out in Patent No. 2,229,249, each code comprises a series of steps, usually sixteen in number, each step being relatively long or short to provide code character. The first step of each control code transmitted from the office is a long step, and the code is thereby rendered distinguishable from indication codes originating at the field stations in each of which the first step is relatively short.

In the control codes delivered by relay *ICR*, since the line is normally closed, the odd-numbered steps correspond to the line open, and the even-numbered steps to the line closed condition. On the other hand, the carrier current circuits are normally open, and the codes are opposite in phase, current being supplied to antennas *A* and *A1* on the odd-numbered steps and not on the even-numbered steps. In the indication codes delivered to the line circuit by relay *T*, the odd-numbered steps represent an increase in the line current above normal, and the even-numbered steps a return to the normal value of the line current.

I shall now describe the operation of the apparatus of Figs. 1A and 1B, assuming first that relay *OM* becomes energized to initiate the transmission of a control code. The closing of front contact *e* of relay *OM* connects the transmitter relay *OT* to the coding unit to cause relay *OT* to

operate periodically in accordance with the code. When relay *OT* is energized, its repeating relay *TC* becomes energized over a circuit extending from one terminal *B* of a suitable local source of current over contact *b* of relay *OT* through relay *TC* to the other terminal *C* of the same source, and relay *TC* delivers the code as carrier current impulses of the frequency generated by oscillator *OSC* to antenna *A*. Relay *OT* also completes a circuit from terminal *B* at its front contact *f* over contact *h* of relay *OM* through the lower winding of relay *OR* to terminal *C*, so that relay *OR* is operated locally in accordance with the code, energizing the timing relays *OL1*, *OL2*, *OLB* and *OLBP* in the usual manner. Relay *PC* is not operated, its circuit being open at contact *j* of relay *OM*, and consequently relays *PCP* and *TS* are not operated.

The radio signals transmitted from antenna *A* are received over antenna *A1* to cause relay *ICR* to respond and to retransmit the code by the operation of its contact *a* to line Y_1-Z_1 , so that the line relay *R* at each station responds in accordance with the code generated by the office transmitter relay *OT*. Each time relay *ICR* operates it completes a circuit from terminal *B* of the local source of current at its left-hand contact *b* through relay *LB* to terminal *C*. Relay *LB* picks up in response to the first operation of relay *ICR* and is held picked up by intermittent energization until the code is completed. Relay *LA* is steadily energized over the normal contact *b* of relay *IR*, and as soon as relay *LB* picks up it completes a circuit from terminal *B* at a contact *a* of relay *LA* over contact *f* of relay *LB* through relay *LC* to terminal *C* so that relay *LC* picks up and is held energized until the code is completed.

Since relay *IR* is operable to reverse in response to an increase in line current, the effect of the opening of the line by the first operation of contact *a* of relay *ICR* is to tend to operate relay *IR* to the left to the position it already occupies. When relay *LB* picks up, its contact *d* shunts the upper winding of relay *IR* connected to transformer *40* and contact *b* of relay *LB* completes a circuit from the middle terminal *O* of the local source through the lower winding of relay *IR* over back contact *f* of relay *PC* to terminal *C* at contact *b* of relay *LB*, whereby relay *IR* is held in its normal position until the transmission of the code by relay *ICR* is completed.

Assuming next that a code is initiated by the energization of a station relay *M* when the system is at rest with relay *OM* released. Contact *j* and *k* of relay *M* reverse the connections to relay *R* and contact *k* of relay *M* also completes a connection from line Y_1 over contact *d* of relay *LBP* and contact *b* of relay *E* to line Z_1 . Contact *e* of relay *M* connects relay *T* to the coding unit and relay *IT* picks up and releases periodically in accordance with the code, the first step of which is relatively short and is terminated by the release of relay *T* following the energization of relay *LBP*, the latter relay being controlled like relay *OLBP* shown in Fig. 1A. After relay *LBP* picks up the line wires Y_1-Z_1 are connected together over contact *b* of relay *T* and the circuit for relay *R* which when relay *M* is energized includes back contact *b* of relay *T*, is now open. When relay *T* releases, relay *R* picks up only if the line current is of the reverse polarity with line Z_1 positive.

At the repeater station the initial increase

in line current due to the operation of relay M causes relay $\text{I}R$ to reverse, completing a circuit from terminal B over its reverse contact c and back contact e of relay LB through relay IPC to terminal C, so that relay IPC become energized supply current from oscillator OSC to antenna A $\dagger$. At the same time, a circuit is closed from terminal B at the right-hand contact b of relay ICR over the reverse contact a of relay IR and front contact b of relay LA through relay IPC to terminal C, and relay IPC picks up. The operation of the contacts b and d of relay IPC reverses the line polarity as required for the continued operation of relay R at the transmitting station and at the same time releases relay R at each other station at which relay M has not been operated. Relay LB now picks up over the circuit from terminal B at the reverse contact b of relay IR and contact e of relay IPC through relay LB to terminal C, and relay LC picks up over contact f of relay LB. Relay IR is held reversed during the reversal of the line polarity by relay IPC because its upper winding is temporarily shunted over front contact c of relay IPC and back contacts e of relays LB and LC, and its lower winding is temporarily energized in a direction to hold it reversed over the circuit extending from terminal B at back contact a of relay LB or LC over front contact f of relay IPC through the lower winding of relay IR to terminal C.

The radio impulse transmitted from antenna A $\dagger$ when relay IPC is energized is received at the office over antenna A and operates relay OR to reverse, thereby energizing relays O $\text{I}G$, O $\text{E}Z$, O LB and O LBP in the usual manner, and completing a circuit temporarily from terminal B at the reverse contact a of relay OR over back contacts f of relay O LBP , f of relay OM, and e of relay O $\text{I}G$ through relay PC to terminal C, so that relay PC picks up establishing a stick circuit at its own front contact a when relay O LBP picks up. Relay OR also completes a circuit temporarily from terminal B at its reverse contact a over contacts g of relays PC, O $\text{I}G$ and O LBP through relay TS to terminal C. Relay TS picks up and completes a circuit from terminal B at its front contact a over back contact h of relay OM through the lower winding of relay OR to terminal C. The operation of relay TS is timed to correspond with that of the station transmitter relay T, and relay OR is held reversed by relay TS for the same length of time on the first step of an indication code as if it were controlled directly by relay T, and so operates its coding unit CU properly, even though the initial radio impulse received is of relatively brief duration.

This arrangement is provided for the reason that the first code step as transmitted by the repeater station is made somewhat shorter than the first step delivered by relay T, being terminated by the release of relay IPC when relay LB picks up to open its contact e . It follows that when relay T releases to begin the second step of the code, relay ICR is already connected to antenna A $\dagger$ so as to be responsive to the operation of the office relay TC and remains released only if the office apparatus is in condition to receive the code, that is to say, only if relay OM has not been operated. If relay ICR remains released until relay IR is operated to normal by the release of relay T, the directional relay Z picks up over the circuit from

terminal B at the right-hand contact b of relay ICR , the normal contact a of relay IR , contact g of relay IPC , contact d of relay LC through relay Z to terminal C. Relay Z by closing its front contact b conditions relay IPC to repeat the code received by relay IR from the field station as a code of radio impulses to which relay OR is responsive.

The office relay OM is prevented from picking up after relay O $\text{I}G$ becomes energized as explained in Patent No. 2,229,249, consequently relays TC and ICR remain released until the indication code transmitted by relay T is completed. Relays LA and LB are held picked up by intermittent energization over the normal and reverse contacts b of relay IR , and consequently relay LC is held energized until the code is completed, while relays Z and IPC are held energized over stick circuits extending from terminal B at the right-hand contact b of relay ICR , contact b of relay LC, and their respective contacts a and windings to terminal C.

In order to minimize the time interval between successive codes, the circuits are so arranged that the coding units are all restored to normal at the end of a complete indication code at approximately the same time. When relay OR at the office is restored to normal at the end of an indication code, a relay O $\text{I}G$ responds and completes a circuit from terminal B at the left-hand contact a of relay OR over front contacts c of relays PC and O $\text{I}G$ and back contact e of relay OM through relay OT to terminal C, whereby relay OT is momentarily energized to cause relay TC to deliver a single pulse to antenna A to which relay ICR at the repeater station responds, thereby releasing relays IPC and Z. Relay IPC restores the polarity of the current supplied to line Y $\dagger$ —Z $\dagger$ to normal to cause relay R at each station other than the transmitting station to become energized and at that station relay R is also energized, relay M releasing to render it responsive to line current of normal polarity.

In the event that the code is incomplete and the operation of relay OR is terminated without operating relay O $\text{I}G$, due to a fault, relay PC is released by the timing relay O LBP and completes a circuit momentarily for relay OT over back contacts c of relays O $\text{I}G$ and PC and front contact c of relay PCP, whereby relays TC and ICR are caused to operate to restore the system to normal.

When an indication code is initiated as above described, a short propagation time may elapse before its effect becomes manifest at the office, during which relay OM may be energized to initiate a control code so that relays PC and OM may pick up together. In this case relay PC releases due to the opening of contact j of relay OM in its circuit, relay OM remaining energized, and relay OT picks up and energizes relay TC, so that when relay IPC at the repeater station releases during the first step of the indication code delivered by relay T as hereinbefore described, relay ICR picks up opening the line Y $\dagger$ —Z $\dagger$ and releasing relay IPC , but holding relay LB energized. Relay IPC opens its front contact g in the pick-up circuit for relay Z and by closing its back contact f restores relay IR to normal. The long first step delivered by relay ICR prevents the further operation of the station transmitter T and so leaves the office transmitter OT in control of the transmission of the remainder of the code. It will be noted that the direction of transmission in this case is deter-

mined by whether the office relay OM picks up or not, the same as when a repeater is not used.

It will be seen that in the carrier current system as shown it is unnecessary to employ frequency discriminating circuits to prevent the operation of the receiving relay such as 1CR by current from the associated oscillator OSC, since these are connected to the antenna in opposite positions of the transmitter relay 1TC. It follows therefore that the same, or approximately the same, carrier frequency may be used for transmission in both directions and that only one carrier frequency or radio channel is required. Furthermore the system of my invention is suitable for use where the attenuation is high, that is to say, where relatively high transmitted energy and a correspondingly sensitive receiving relay are required.

In the system described it is the practice to provide disconnecting apparatus at each field station, such as is shown in my application Serial No. 468,224, filed December 8, 1942, for Remote control systems, now Patent No. 2,376,569, issued May 22, 1945, whereby the operator at the control office can disconnect the apparatus at any station at will, and thereby prevent interference in the case of a fault. This is accomplished by the operation of a push button PB, shown in Fig. 1A, for a period relatively long in comparison with the lengths of the code steps.

If button PB is operated during the transmission of an indication code as above described, relay TC is steadily energized, preventing relay OR from receiving the code and causing relay 1CR to become energized as soon as relay 1TC releases to transmit an even-numbered code step. Relay 1CR opens the line circuit, operating relay 1R to normal, and releases relays 1PC and Z. and relay 1PC on releasing holds relay 1R normal, so that relay 1TC remains released, relay 1CR then holding line Y1-Z1 open so that relay R remains released to correspond with the steady energization of relay TC. It will be seen that since the operator is thus able to reverse the direction of transmission through the repeater station at will, the distant line circuit is at all times controllable from the office.

Referring now to Fig. 2A, in this view a modification of Fig. 1A is shown in which the carrier circuit apparatus associated with antenna A is located at a distance from the office and connected thereto by a pair of line wires Y-Z over which the codes are transmitted in two directions. The office apparatus in this view is arranged in the same manner as when the office and stations are connected by a physical line circuit as described in Patent No. 2,350,668, including a master relay OM controlling a transmitter relay OT by which the current supplied to line Y-Z by battery OB is interrupted to transmit control codes, and the receiving relay OR is of the stick polar type connected to the line through an impulse transformer 40 like relay 1R in Fig. 1B and is similarly responsive to line current variations. The office coding unit of Fig. 2A also includes a pole changer relay PC and an auxiliary relay TS, which function like the similar relays of Fig. 1A already described.

The apparatus of Fig. 2A may be used with that of Fig. 1B already described, in which case the communication channel includes three sections, one including the line wires Y-Z, another comprising the radio channel including the antennas A and A1, and a third including the line Y1-Z1 extending to the field stations, as shown

in Fig. 1B. The first repeater station, as shown in Fig. 2A, serves to repeat the codes between the line Y-Z and the radio channel, and includes two biased polar line relays PR and NR connected oppositely across line Y-Z in series with a relatively high resistance 20, together with a slow acting relay NP controlled by relay NR, and carrier current apparatus including a transmitter relay TC and a receiving relay CR associated with antenna A as in Fig. 1A. Normally the polarity of the current supplied by battery OB to line Y-Z is such that relay PR assumes its energized position and relay NR its released position, as shown, and when the line polarity is reversed by the office relay PC, relay NR assumes its energized position and relay PR its released position. When the line Y-Z is opened by the operation of relay OT, relay PC releases to complete a circuit from terminal B over the normal contacts a of relays NR and CR and the reverse contact a of relay PR through relay TC to terminal C. Relay TC therefore repeats the operation of relay OT to deliver control codes to antenna A as in Fig. 1A, to which relay 1CR of Fig. 1B or 2B is responsive.

When a radio impulse is received over antenna A of Fig. 2A, due to the initiation of an indication code by a station transmitter relay T, relay CR responds and shunts resistor 20 increasing the current in line Y-Z so as to reverse relay OR, whereupon relay PC becomes energized as hereinbefore described, reversing the polarity of the current supplied to line Y-Z causing relay PR to release and relay NR to become energized. The operation of contact a of relay NR to the right disconnects terminal B from the circuit for relay TC, and causes the slow release relay NP to become energized. The indication code transmitted by relay T is repeated by relays CR and OR in the manner described above in connection with Figs. 1A and 1B, relay PC being released by a relay O16 at the end of the code. In the previous example, the code was followed by the transmission of a single impulse by relay TC at the office for the purpose of releasing relay 1PC of Fig. 1B. In the present instance, the restoration of the polarity of line Y-Z to normal by relay PC at the end of the code causes relay PR to assume its energized position and relay NR to assume its released position, deenergizing relay NP, and the circuit for relay TC is then closed momentarily over contact a of relay NP and contact b of relay NR, with the same result.

In Fig. 2A the operation of button PB disconnects battery OB from the line so that relays PR and NR both are released and relay TC is steadily energized. Relay TC is also energized if relay OT is operated to initiate a control code at the same time that relay T is operated to initiate an indication code, the operation of Fig. 2A being identical with that of Fig. 1A as already described, in these respects.

Referring now to Fig. 2B, the apparatus as shown is arranged for the control of stations connected to a line Y1-Z1 which is similar to that of Fig. 1B, and in addition thereto another set of apparatus interlocked therewith is provided for the control of another group of stations connected to a second line Y2-Z2. In Fig. 2B, the operation of the receiving relay 1CR in response to a control code transmitted by the office apparatus of Fig. 1A or 1B causes the delivery of the control code to both lines by the operation of its contacts a and c, respectively, and at the same time operates relays LB and LC as already described in connection with Fig. 1B.

Assuming first that an indication code is initiated at a station on line YX-Z1, relay 1R reverses energizing relays 1TC and 1PC and transmitting a radio impulse to the office from antenna A1, as already described. The reversal of polarity in line Y1-Z1 by relay 1PC releases the line relays at other stations on that line, and those on line Y2-Z2 are released by the opening of the latter at contact h of relay 1PC, until the code is completed. Similarly, the initiation of a code at a station on line Y2-Z2 causes relay 2R to reverse, energizing relays 1TC and 2PC, contact h of relay 2PC opening line Y1-Z1. In the event relays 1R and 2R are both reversed at the same time, only relay 1PC remains energized, its contact j opening the circuit for relay 2PC. The release of relay 2PC places relay 1R under the control of line Y1-Z1 to continue its operation and restores relay 2R to normal.

Inasmuch as relays 1R and 2R are operable to deliver codes only one at a time, it will be apparent that only one set of relays LA, LB, LC and Z are required in Fig. 2B. Although the total number of stations which may be controlled by the apparatus of Fig. 2B is no greater than in Fig. 2A, this being limited by the capacity of the office coding unit and being 35 stations in the system described, the repeater of Fig. 2B has the advantage that it may be located at any convenient point in the controlled territory where suitable power supply and maintenance facilities are available to control stations in opposite directions and it is unnecessary to locate it at one end of the line.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In a remote control system, a repeater connecting two communication circuits including a receiving relay controlled over each circuit for repeating received impulses into the circuit for the other, each such relay being controlled by the other to render it non-responsive to repeated impulses, a first and a second stick relay each having pick-up and stick circuits controlled over a normally closed contact of one of said receiving relays, means including a normally open contact of the other receiving relay for completing the pick-up circuit for the first stick relay as soon as such relay starts to repeat received impulses into the circuit for said one receiving relay, means responsive to the operation of said first stick relay for terminating the control of the circuit for said one receiving relay by the other and for rendering said one receiving relay effective to repeat code impulses in the opposite direction through said repeater in the event impulses are received from both circuits at the same time, means including a front contact of said first stick relay and a normally closed contact of said other receiving relay for completing the pick-up circuit for the second stick relay only if said one receiving relay is not operated during the reception of the first impulse of a code by the other, and means controlled by said second stick relay when energized for again rendering said other receiving relay effective to repeat the remaining impulses of the code received thereby into the circuit for said one receiving relay.

2. In a remote control system, a repeater station including two receiving relays, a communication channel extending from said repeater station to a control office, a code transmitter at said office for supplying codes of impulses to said channel to which one of said receiving relays is responsive, a line circuit extending from said repeater station to a remote station, a code transmitter at said remote station for supplying codes of impulses to said line circuit to which the other receiving relay at the repeater station is responsive, code receivers at the office and station, means including contacts of said one receiving relay for repeating the code impulses received from said channel to said circuit to operate the station receiver but without operating the other receiving relay at said repeater station, means including contacts of the other receiving relay operated in response to the first impulse of a code received from the station for supplying a relatively brief impulse to said channel to which said office receiver is responsive but without operating said one receiving relay controlled over said channel, and means effective only if said one receiving relay remains in its non-operated condition following the transmission of said brief impulse for conditioning said other receiving relay to repeat the remaining impulses of the code received from the station into said channel.
3. In a remote control system, an office and a station, a first and a second communication channel connected by a two way repeater, including a repeating relay in each channel each responsive only when the other is in its normal non-operated position for repeating code impulses received from one channel into the other in either direction, code transmitters at a control office and at a remote station for supplying code impulses to said first and to said second channel respectively, a stick relay in said repeater, a circuit for energizing said stick relay closed in response to an impulse received from said second channel due to the initiation of a code by the station transmitter, means controlled by said stick relay when energized conditioning said station transmitter to complete its code, means for holding said stick relay energized only so long as the repeating relay in said first channel remains in its normal position, means for locally terminating the first impulse of the code repeated into said first channel to render the repeating relay in the first channel responsive prior to the termination of the first impulse received from the second channel in the event an impulse is being supplied by the office transmitter to said first channel at the time whereby said stick relay is released and the operation of the station transmitter is discontinued before completing the first impulse of its code.
4. In a remote control system, a first and a second communication channel connected by a two way repeater including a repeating relay in each channel, each responsive only when the other is in its normal non-operated position for repeating code impulses received from one channel into the other in either direction, code transmitters at a control office and at a remote station for supplying code impulses to said first and to said second channel respectively, receiving relays at the office and station responsive to impulses received over said channels, a stick relay in said repeater, a circuit for energizing said stick relay closed in response to an impulse received from said second channel due to the initiation of a code by the station transmitter, means controlled by said stick relay when energized conditioning said station transmitter to complete its code, means for holding said stick relay energized only so long as the repeating relay in said first channel remains in its normal position, means for locally terminating the first impulse of the code repeated into said first channel to render the repeating relay in the first channel responsive prior to the termination of the first impulse received from the second channel in the event an impulse is being supplied by the office transmitter to said first channel at the time whereby said stick relay is released and the operation of the station transmitter is discontinued before completing the first impulse of its code.

tiation of a code by said station transmitter, means effective only when said stick relay is energized for conditioning the station transmitter to continue the transmission of its code, a holding circuit for said stick relay closed only so long as the repeating relay in said first channel remains in its normal position, means causing the first impulse repeated into said first channel to be of relatively brief duration and for rendering the repeating relay therein responsive during the reception of the first code impulse from said station transmitter whereby its continued operation is rendered dependent upon the non-operation of the office transmitter, and means at the office responsive to said impulse of brief duration received over the first channel for locally holding said receiving relay in its operated position for a time corresponding to the duration of the first code impulse supplied by the station transmitter to said second channel.

5. In a remote control system, an office and a repeater station, two normally energized line circuits including sources of current at said repeater station and extending through different remote stations, code transmitters and receivers at the office and at each remote station, a receiving relay at the repeater station having a normally closed contact in each line circuit, a line relay for each line circuit responsive to current variations therein at the repeater station, means controlled by the office code transmitter for transmitting codes of carrier current impulses to which said receiving relay is responsive to control the receivers at the stations on both line circuits, means for setting the code transmitter at each remote station into operation when the adjacent line circuit is energized to vary the current therein periodically in accordance with a code, means controlled by each line relay for transmitting carrier current impulses to which the office receiver is responsive in accordance with such code, two stick relays at the repeater station including one for each line circuit each having a back contact in the line circuit for the other, means responsive to the initiation of a code by a transmitter at a remote station for energizing the corresponding stick relay, a holding circuit for each stick relay including a normally closed contact of said receiving relay, means controlled by such stick relay when energized for conditioning the station transmitter to complete its code, means comprising a back contact of one stick relay included in the circuits for the other to cause only one stick relay to remain energized when both are operated at the same time, and means controlled by the office receiver for transmitting a single impulse of carrier current to which the receiving relay at the repeater station is responsive to release the energized stick relay upon the reception of a complete code at the office.

6. In a remote control system, a carrier current channel for communication between a control office and a repeater station, a line circuit extending from said repeater station to a

remote station, a code transmitter at said remote station adapted when initiated to deliver a code over said line circuit to said repeater station, a repeating relay at said repeater station responsive to said codes and having contacts for supplying carrier current to said channel to repeat said codes over said channel to the office, a stick relay at the repeater station, means for energizing said stick relay upon the first operation of said repeating relay when a code is initiated by said station transmitter, means controlled by the stick relay when energized to condition the station transmitter to complete its code, two slow acting relays one controlled over a normal contact and the other over a reverse contact of said repeating relay and means dependent upon the continued energization of both of said slow acting relays due to the code operation of said repeating relay for maintaining said stick relay energized only as long as said code transmitter continues its operation.

7. In a remote control system, a control office, a repeater station and a remote station, means for transmitting codes in two directions between the control office and the repeater station, a normally energized line circuit including a source of current at said repeater station and extending to said remote station, a code transmitter at said remote station adapted to initiate the transmission of a code over said line circuit only when it is supplied with current of normal polarity and to continue the transmission of such code only when it is supplied with current of reverse polarity, a line relay at the repeater station for retransmitting such code to the office, a receiving relay at the repeater station having contacts in said line circuit for repeating codes received from the office to the remote station, a first slow acting relay controlled over a normal contact of the line relay, a stick relay having a pick-up circuit including a reverse contact of the line relay and normally closed contacts of the receiving relay and of said first slow acting relay, means comprising contacts of said stick relay for reversing the polarity of the current supplied to the line circuit when said stick relay is energized, a second slow acting relay having one energizing circuit controlled by a normally open contact of said receiving relay and another controlled by normally open contacts of said line relay and said stick relay, a third slow acting relay having an energizing circuit controlled by front contacts of said first and second slow acting relays, a holding circuit for said stick relay including its own front contact, a normally closed contact of said receiving relay and a front contact of said third slow acting relay, and means for locally energizing said line relay in one direction when said stick relay is picked up and said second or third slow acting relay is released and in the other direction when said stick relay is released and said second slow acting relay is picked up.

GEORGE W. BAUGHMAN.
